UNITED STATES PATENT OFFICE.

LE ROY W. FAIRCHILD, OF NEW YORK, N. Y.

DESIGN FOR PENCIL-CASES.

Specification forming part of Design No. **11,435**, dated September 23, 1879; application filed August 16, 1879.
[Term of patent 7 years.]

To all whom it may concern:

Be it known that I, LE ROY W. FAIRCHILD, of the city, county, and State of New York, have produced a new and Original Design for an Ornamental Pencil-Case, or case for small implements, of which the following is a full, clear, and exact description, reference being had to the accompanying engraved illustration, making a part of this specification.

A is a representation of a complete design, including the pencil-case retracted, and its ornamental inscription-scroll and laurel wreath.

The case is substantially in the form of an ordinary metallic shell and ball cartridge for small arms with the ring *b* held loosely in an eye at the base or solid end, as shown at *c*.

d is a narrow shoulder projection within the outer case. *e* is a projecting bead in imita-

tion of the cartridge-rim. *f* is a scroll, formed in relief upon the case, intended for an inscription or name. *g* is a wreath in imitation of laurel or other foliage encircling spirally the shell or case from the bead *e* to its conoidal end, or nearly so. *h* is the conoidal end of the case proper.

Different colors may be used, if desired.

What I claim as my invention is—

A design for a pencil-case, consisting of the outer shell or case in the form of a cartridge, the ring *b*, eye *c*, shoulder projection *d*, bead *e*, scroll *f*, and wreath *g*, substantially as shown and described.

LE ROY W. FAIRCHILD.
